his Attorney.

UNITED STATES PATENT OFFICE.

FRANK A. ROBINSON, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,075,496.

Specification of Letters Patent. Patented Oct. 14, 1913.

Application filed June 10, 1912. Serial No. 702,682.

To all whom it may concern:

Be it known that I, FRANK A. ROBINSON, a citizen of the United States, residing in borough of Brooklyn, city of New York, 5 in the county of Kings and State of New York, have invented certain new and useful Improvements in Type-Writing Machines, of which the following is a specification.

My invention relates to typewriting machines, and particularly to means for feeding 10 a work-sheet around the platen of a typewriter.

The paper or other work-sheet is provided with perforations along its edge 15 spaced at uniform intervals, and on one or both ends of the platen, studs are provided spaced at corresponding intervals, and arranged to enter said perforations and positively aline the work-sheet as it is fed around 20 the platen. The row of studs on the end of the platen preferably extends only part way around it, so that the work-sheet may be inserted when the platen is properly placed without interference from any of the studs. 25 A stop is preferably provided arresting the platen at the most convenient point for inserting the paper free from interference from said studs; and guides, such as envelop guides, may be arranged to hold the work- 30 sheet so that as it travels around the platen, it is always engaged by at least two studs, and therefore is held positively alined by said studs.

Other features and advantages will here- 35 inafter appear.

In the accompanying drawings, Figure 1 represents a partial section through an Underwood typewriting machine showing my invention as applied thereto. Fig. 2 is a 40 figure partly diagrammatic showing the platen and its relation to the work-sheet. Fig. 3 is a bottom view of a typewriter carriage showing my invention as applied thereto. Fig. 4 is an end view of the platen and 45 its line space mechanism. Fig. 5 is a view partly sectional showing the end of the platen and its stop.

On the frame 1 of an Underwood typewriting machine, a carriage 2 travels in the usual 50 manner, said carriage comprising the usual platen frame having ends 3 and 4, on which ends a platen 5 is journaled. Said platen may be rotated by hand wheel 6 to feed a work-sheet 7 around it, said work-sheet being 55 first placed on a paper table 8 and moved

by hand forwardly around under the platen until it comes over the pins or studs 9 which have been placed in the position seen in Fig. 4. In this position there are no studs to interfere with the work-sheet as it passes under 60 the platen. Also in this position the conical pins or studs 9, which are fast on the platen, are in sight, and said work-sheet 7 may be easily adjusted on the platen so that its perforations register with said studs 9 and positively aline the sheet. When so alined guides 11 and rear envelop guides 12 may be swung so as to hold said work-sheet close 65 around the platen, so that the work-sheet will always engage at least two of said studs 70 9. In addition to the hand wheel 6, the platen may be rotated by the usual line-space lever 13 working through a slide 14, to drive a line-space wheel 15, fast on the axle 16 of said platen, and the throw of said 75 line-space wheel may be regulated by a finger-piece 15^a. The platen is positively brought to rest in the position shown in Fig. 4 which is the most desirable position for inserting a work-sheet, by means of a 80 spring-operated stop 17 adapted to enter an opening 18 in said platen and to positively lock said platen when rotated in reversed direction. A cam face 19 on said stop permits the platen to rotate freely in line-spac- 85 ing direction and a handle 20 on said stop is arranged to move it to inoperative position whenever it is desired to reverse the rotation of the platen. The paper table 8, where it becomes a paper guide 21 close against the 90 platen, may be cut away at 22 to permit the studs 9 to pass, and the usual pressure rolls 23 may be provided to assist the paper in its feed around the platen.

It will be observed that on each end of 95 the platen there are only six of the studs 9, and these are all on about one-third of the circumference of the platen. The guides 11 and 12 are preferably so arranged to hold the work-sheet against enough of the circum- 100 ference of the platen, so that at least two studs on one end will at all times be engaged with their perforations in the work-sheet. This insures that if the work-sheet engages the studs on even only one end of the platen, 105 it will be alined by the studs on that end. The perforations 10 of the work-sheet may be arranged to coöperate with such devices as loose-leaf ledgers, if desirable, or they may form merely a temporary extension of 110

said sheet which is arranged to be torn off along a line of cuts 24 after the work-sheet is removed from the typewriter. The studs 9 are preferably mounted on a metallic extension 25 of the platen 5.

5 The studs 9, at every revolution of the platen, are made alternately inaccessible (Fig. 1) and accessible (Fig. 4); and in getting ready to insert a sheet, the operator rotates the platen to bring the studs to the accessible Fig. 4 position, at which point the platen is arrested by the stop 17, which is effective only once in every revolution of the platen. The operator then swings aside the 10 paper guides 12 at the introductory side of the platen; which are similar to the members 11, usually employed in the Underwood machine to run on the delivery side of the platen, for assisting in feeding envelopes 15 around the platen. The operator then inserts the work-sheet between the platen and the paper shelf 8; the sheet passing down around the under side of the platen between the same and the paper guide 21, and then 20 up in front thereof, where it passes beneath the paper guide 11; and the perforations 10 are caught upon some of the foremost studs 9. The operator then swings the guides 12 to effective positions, Fig. 1, and then may 25 release the detent 17 and proceed to rotate the platen in the usual manner for advancing the work-sheet line by line.

It will be seen that the rolls carried on the ends of the guides 11 and 12 are so near 30 each other, that they hold the work-sheet wrapped around the platen for nearly the entire circumference of the platen, or at least sufficiently to cause some of the sheet perforations 10 to be always caught upon the 35 studs 9. The operator may proceed to revolve the platen during the writing, until the sheet is run off from the platen; or at any time, he may rotate the platen to the Fig. 4 position, and swing aside the guides 40 11, 12, and withdraw the partly written 45 sheet.

Variations may be resorted to within the scope of the invention, and portions of the improvements may be used without others.

50 Having thus described my invention, I claim:

1. In the paper feed mechanism of a typewriting machine, a rotatable platen having work-carrying studs thereon arranged at 55 uniform intervals to engage similarly arranged perforations in a work sheet, said studs being placed in an arc extending part way only, around the platen, whereby a part of the circumference of the platen is left unobstructed for the free insertion of a work sheet.

2. In the paper feed mechanism of a typewriting machine, the combination of a rotatable platen having work-carrying studs 60 thereon arranged at uniform intervals to

engage similarly arranged perforations in a work sheet, said studs being placed in an arc extending part way only, around the platen, whereby a part of the circumference of the platen is left unobstructed for the free insertion of the work sheet, and means to hold the work sheet against the platen for a sufficient portion of the circumference thereof to be always engaged by said studs.

3. In the paper feed mechanism of a typewriting machine, the combination of the rotatable platen having work-carrying studs thereon arranged at uniform intervals to engage similarly arranged perforations in a work sheet, said studs being placed in an arc extending less than half the way around the platen, whereby the greater part of the circumference of the platen is left unobstructed for the free insertion of a work sheet, and releasable means to hold the work sheet against the platen for a sufficient portion of the circumference thereof to be always engaged by the studs.

4. In the paper feed mechanism of a typewriting machine, a rotatable platen having two rows of work-carrying studs thereon arranged at uniform intervals to engage similarly arranged perforations in a work sheet, said studs being placed in parallel arcs extending part way only, around the platen, whereby a part of the circumference of the platen is left unobstructed for the free insertion of a work sheet.

5. In the paper feed mechanism of a typewriting machine, the combination of a rotatable platen having work-carrying studs thereon arranged at uniform intervals to engage similarly arranged perforations in a work sheet, said studs being placed in an arc extending part way only, around the platen, whereby a part of the circumference of the platen is left unobstructed for the free insertion of a work sheet, and a stop for arresting said platen when said studs are in accessible position, so that a work sheet may be caught upon them.

6. In a typewriting machine, the combination with a rotatable platen, of a row of equally spaced studs around less than half of the circumference of said platen, a paper guide close to said platen and having a portion cut away to permit said studs to pass, and a stop for arresting said platen when the part of said platen free from said studs is adjacent said paper guide.

7. In the paper feed mechanism of a typewriting machine, the combination with a rotatable platen, of a group of spaced studs on the circumference of said platen, said group occupying less than one-half of the circumference of said platen, whereby a perforated work sheet may be readily adjusted upon the unoccupied arc of the platen into engagement with some one or more of the studs and means to hold said sheet in such

engagement during any desired arc of revolution of the platen.

8. In the paper feed mechanism of a typewriting machine, the combination with a rotatable platen, of a group of spaced studs on an arc of the circumference thereof, and arranged to enter perforations in a work-sheet, said group occupying less than half of said circumference, and guides arranged to hold a work-sheet against so much of said platen that said sheet always engages with a pin.

9. In the paper feed mechanism of a typewriting machine, the combination with a rotatable platen, of a group of spaced studs on a circumference thereof, and arranged to enter perforations in a work-sheet, said group occupying less than half of said circumference, and guides movable out of the path of said work-sheet but arranged to be shifted to hold said work-sheet wrapped around said platen sufficiently to always engage a pin.

10. In the paper feed mechanism of a typewriting machine, the combination with a rotatable platen, of a group of studs arranged in an arc part way around said platen to engage a work-sheet, a paper guide close against one side of said platen, a spring operated stop arranged to arrest said platen in its backward rotation when said non-engaging part is adjacent said guide, and a handle for throwing said stop to inoperative position.

11. The combination with a revolute platen, of a series of work-carrying studs projecting from its periphery at each end thereof, one series being opposite the other, and each series extending around less than half the circumference of the platen, whereby a work sheet may be adjusted past the unobstructed part into engagement with one or more of the studs, and means to hold the work-sheet wrapped sufficiently far around the platen to insure it always being caught upon the studs.

12. The combination with a revolute platen, of a series of work-carrying studs projecting from its periphery at each end thereof, one series being opposite the other, and each series extending around less than half the circumference of the platen, whereby a work sheet may be adjusted past the unobstructed part into engagement with one or more of the studs, and means to hold the work-sheet wrapped sufficiently far around the platen to insure it always being caught upon the studs; said sheet-holding means comprising both a paper-guiding device at

the introductory side of the platen and a paper guiding device at the delivery side of the platen.

13. The combination with a revolute platen, of a series of work-carrying studs projecting from its periphery at each end

thereof, one series being opposite the other, and each series extending around less than half the circumference of the platen, whereby a work sheet may be adjusted past the unobstructed part into engagement with one or more of the studs, means to hold the work-sheet wrapped sufficiently far around the platen to insure it always being caught upon the studs, and means for arresting said platen at such a position thereof, that the sheet being introduced around the platen may clear the studs.

14. The combination with a revolute platen, of a row of work-carrying studs extending partly around the circumference thereof, said row sometimes accessible and sometimes inaccessible for the insertion of a work sheet during the rotation of the platen, and means to cause a work-sheet to be caught upon said studs to be carried continuously thereby during successive revolutions of the platen in the same direction.

15. The combination with a revolute platen, of two rows of work-carrying studs extending partly around the circumference thereof at its opposite ends, said rows sometimes accessible for the insertion of a work sheet and sometimes inaccessible during the rotation of the platen, and means to cause a work-sheet to always be caught upon the studs in both rows to be carried thereby.

16. The combination with a revolute platen, of a row of work-carrying studs extending partly around the circumference thereof, said row sometimes accessible and sometimes inaccessible for the insertion of a work sheet during the rotation of the platen, means to cause a work-sheet to be caught upon said studs to be carried continuously thereby during successive revolutions of the platen in the same direction, and means to coöperate with said studs to hold a work-sheet thereon so that the sheet will always be caught by the studs.

17. The combination with a revolute platen, of a row of work-carrying studs extending partly around the circumference thereof, said row sometimes accessible and sometimes inaccessible for the insertion of a work sheet during the rotation of the platen, means to cause a work-sheet to be caught upon said studs to be carried continuously thereby during successive revolutions of the platen in the same direction, and means to coöperate with said studs to hold a work-sheet thereon so that the sheet will always be caught by the studs; said means being releasable to permit the insertion and withdrawal of the work-sheet.

18. The combination with a revolute platen, of a row of work-carrying studs extending partly around the circumference thereof, said row sometimes accessible and sometimes inaccessible for the insertion of a work sheet during the rotation of the platen,

means permitting a work-sheet to be caught upon said studs to be carried continuously thereby during successive revolutions of the platen in the same direction, means to co-
5 operate with said studs to hold a work-sheet thereon so that the sheet will always be caught by the studs; said means being re-
leasable to permit the insertion and with-

drawal of the work-sheet, and a special ar-
resting device for the platen effective only 10
when the studs are in accessible positions.

FRANK A. ROBINSON.
